Des. 214,575
Patented July 1, 1969

214,575

CHILD'S PLAY CART

Glen E. Fravel, 8005 N. Van Houten Ave.,
Portland, Oreg. 97203

Filed Jan. 22, 1968, Ser. No. 10,251

Term of patent 14 years

Int. Cl. D12—10; D21—02
U.S. Cl. D34—15

FIG. 1

FIG. 2

FIG. 3

FIG. 4

FIGURE 1 is a side elevational view of a first form of child's play cart showing my new design;

FIGURE 2 is an end view of the cart taken from the right side of FIGURE 1;

FIGURE 3 is a top plan view of the cart;

FIGURE 4 is a bottom plan view of the cart.

I claim:

The ornamental design for a child's play cart, as shown.
